Loy E. Hiskey, Sterling, Colo.

Application May 24, 1949, Serial No. 2,844

Term of patent 14 years

(Cl. D93—4)

To all whom it may concern:

Be it known that I, Loy E. Hiskey, a citizen of the United States of America, residing at Sterling, in the county of Logan and State of Colorado, have invented a new, original, and ornamental Design for Electric Putty Softeners, of which the following is a specification, reference being had to the accompanying drawing, forming part thereof.

In the drawing:

Fig. 1 is a top view of an electric putty softener, showing my new design;

Fig. 2 is a side view thereof;

Fig. 3 is a bottom view thereof; and

Fig. 4 is an end view thereof.

I claim:

The ornamental design for an electric putty softener, as shown.

LOY E. HISKEY.
